(57) **CLAIM**

The ornamental design for a heating apparatus, as shown and described.

DESCRIPTION

FIG. 1 is a perspective view of a heating apparatus according to our new design;

FIG. 2 is a front elevation view of the heating apparatus of FIG. 1,

FIG. 3 is a rear side elevation view of the heating apparatus of FIG. 1,

FIG. 4 is a top view of the heating apparatus of FIG. 1,

FIG. 5 is a bottom view of the heating apparatus of FIG. 1; and,

FIG. 6 is a left side elevation view of the heating apparatus of FIG. 1, the right side elevation view being a mirror image thereof.

The broken lines showing in the Figures are included for the purpose of illustrating environment of the design and form no part of the claimed design.
